UNITED STATES PATENT OFFICE.

NEWELL H. MOTSINGER, OF GREENSBURG, PENNSYLVANIA.

ROTARY ENGINE.

960,993.

Specification of Letters Patent. Patented June 7, 1910.

Application filed March 5, 1906, Serial No. 304,412. Renewed December 20, 1909. Serial No. 534,172.

To all whom it may concern:

Be it known that I, NEWELL H. MOTSINGER, a citizen of the United States, residing at Greensburg, in the county of Westmoreland and State of Pennsylvania, have invented certain new and useful Improvements in Rotary Engines, of which the following is a specification.

My said invention consists in certain improvements in the details of construction of that class of rotary engines illustrated in my Patent No. 726,969 of May 5, 1903, whereby the operation thereof is rendered more efficient and economical and its construction more perfect for the purposes designed, all as will be hereinafter more fully described and claimed.

Referring to the accompanying drawings, which are made a part hereof and on which similar reference characters indicate similar parts, Figure 1 is an axial section through an engine of my improved construction, Fig. 2 a cross-section on the dotted line 2—2 in Fig. 1, Fig. 3 a cross-section on the dotted line 3—3 in Fig. 1, the position of the cylinders being varied to illustrate the relative positions of the vanes and grooves at the point of engagement, Fig. 4 a detail cross-section similar to a portion of Fig. 2 showing the valve in exhaust position, and Fig. 5 a detail cross-section showing a modified construction of the valve.

In said drawings the portions marked A represent the main body or casing of the engine, B and C a pair of co-acting cylinders, D the valve for controlling the inlet and exhaust ports, and E an oil reservoir.

The casing A is a casting of substantially the form in cross section best shown in Figs. 2 and 3, and preferably consists of two duplicate parts abutting, as shown in Fig. 1, and secured together by circumferential flanges on their adjacent ends and clamping bolts *a* extending through perforations in said flanges, the abutting faces of said sections being planed or ground true to provide a steam tight joint. Said casing is provided with ledges *a'* upon which it may set in any suitable base or support and is formed with three cylindrical chambers to receive the rotary valve D, the cylinder B and the cylinder C. It is provided with heads A' and A² containing bearings for the journals of said several parts. Steam inlet ports 1, 2 and 3 are formed through the sides of the casing at each end, the en-

trances to which are located side by side and close together and communicate with the valve chamber, while their discharge ends communicate with the chamber in which cylinder B is mounted and at different points around one side of its circumference, preferably about equal distances apart, as shown.

An exhaust port 4 at each end leads from the opposite side of said chamber through said casing to the opposite side of the valve chamber. This arrangement is clearly shown in Fig. 2 and is the same at both ends of the engine. The arrangement of ports in the center of the casing is substantially the same as at each end, except that they are reversed, the inlet ports 5, 6 and 7 (shown in Fig. 3) leading into the opposite side of the chamber of cylinder B, while the exhaust port 8 leads from the opposite side of said chamber. The corresponding center ports of each section come together and join each other at the center forming practically single ports of double the capacity of each, as indicated by dotted lines in Fig. 1. The chambers for the cylinders B and C are formed with their interior surfaces true circles in cross section and the circle of one cuts into the circle of the other, as shown, so that the peripheries of said cylinders may contact. The opening between said chambers is thus bounded on opposite sides by sharp angles 11 in the casing. The lower edge of each inlet port 1 and 5 is at distance above said angle or point 11 that the grooves in the cylinder C will pass under said point and be closed before the port is opened to admit the fluid pressure and thus guard against said fluid passing into said groove. The entrances to exhaust ports 4 and 8 are also located a sufficient distance above point 11 on the other side so that the groove shall have passed beyond the contact between the cylinders before it is opened, thus guarding against exhaust steam passing into said grooves and through them to the live steam chambers.

The cylinder B is formed in two sections secured rigidly to the shaft B' by means of splines *b* and transverse pins *b'* which extend through said sections and said shaft. Each section is formed with spiral vanes *b*², there being preferably two of said vanes, starting at diametrically opposite points on the cylinder on each section and running in a spiral direction at an angle of forty-five

degrees from one end of each section to the other. The vanes upon one end run in a right-hand direction while those upon the other section run in a left-hand direction, as shown in Fig. 1, the ends of the corresponding vanes of the two sections meeting and joining in the center of the cylinder. Packing strips b^3 may be provided in the faces of said vanes, as shown in Figs. 3 and 4, 10 said strips being T-shaped in cross section and mounted in correspondingly shaped grooves in said vanes and normally held outwardly by springs b^4 mounted in the bottom of said grooves beneath said packing strips. By this means, a tight fit between said vanes and the interior of the chamber in which cylinder B is mounted, may be insured. Each of said vanes b^3 at its base and sides is of the particular form described in 20 my above mentioned Letters Patent, but the outer face of each of said vanes is formed curved on a line coincident with the interior surface of the chamber and said surface is cut on each side to an axial line at that 25 point where the advancing side of the vane in the rotation of the cylinders leaves its close contact with the advancing side of the groove, which point is illustrated in Fig. 3. The advantage of this particular form will 30 be presently described.

The cylinder C is formed in two sections secured to shaft C' by splines c and pins c' in a similar manner as are the sections composing cylinder B. Each of said sections 35 is provided with spiral grooves c^2 formed to receive and co-act with the spiral vanes b^2 upon the cylinder B. The sides of said grooves are of a curve to correspond with and closely fit to the sides of said vanes when 40 in mesh therewith but they extend into the cylinder to meet on the lines of said curvature, thus providing a pocket between the bottom of each groove and the outer face of the vane therein, when in mesh with each 45 other, as best shown in Fig. 3.

The valve D is a hollow cylinder mounted in the valve chamber in the top of casing A and adapted to rotate therein. At one end it projects into an extension of said chamber 50 in head A² and is formed with a series of radial openings which communicate with an inlet pipe D' through which steam or other motive fluid is admitted to the interior of said valve. At each end it is formed with 55 a valve section d extending around about two-thirds of its circumference, as shown in Fig. 3, and having a fan-shaped port d' therethrough. In its middle is another similar valve section d², on its opposite side, having a fan-shaped port d³ therethrough. Between the valve sections d and d² the exterior of said valve D is cored out, forming 60 an exhaust chamber within the valve chamber and surrounding said valve from end to end. Exhaust pipes D² lead from said

chamber to conduct away the exhaust. An operating lever D³ is mounted upon one of the journals d⁴ of said valve.

An oil reservoir E, supplied through a supply pipe e, is preferably mounted upon 70 the top of the casing A and branch pipes e', e², e³ and e⁴ lead therefrom through the sides of the chamber containing the cylinder C to discharge within said chamber at each end and the center thereof. 75

In Fig. 5, I have shown the valve composed of a cylinder D³ with the valve section formed as a separate part d³ mounted thereon, the ports and cored out portions being arranged in the same manner as when 80 formed in one piece but adapted to be adjusted circumferentially on said cylinder D³ by means of a set screw d⁹. By this arrangement, as will be readily understood, the time of opening and closing the ports and the 85 extent to which they are opened and closed may be regulated to suit the work.

In operation, the steam, or other motive fluid, being turned on by means of the operating lever D³, and the parts being in the 90 position shown in Fig. 2, said fluid will come into the ports 1, 2 and 3 behind the vane b^2 and by impact and expansive force against the rear edge of said vane, will operate to drive said cylinder B in the direction indicated by the arrow. As shown by the dotted lines, the mouths of the several inlet ports are formed on an angle equal to the angle of the spiral vanes so that as each vane passes over each port it opens for its 100 full width parallel with the edge of said vane. In Fig. 2, the vane b^2 on the right-hand side of cylinder B is shown in position with the lower edge of port 1 just opening, the dotted line indicating the lower edge of 105 said port, which is parallel with the rear edge of said vane. Cylinder C is in a position where the rear corner 10 of the groove has just passed under the angle 11, before 110 described. The steam, or other motive fluid, coming from port 1 thus discharges into a narrow chamber formed between the solid surfaces of the casing, the cylinders B and C and the rear edge of vane b^2 , all leakage 115 into the groove c^2 being prevented by the mouth of said groove having passed entirely under said angle 11 of said casing, this result being made possible by the vane being 120 cut to the line where it separates from said groove, as shown at the left in Fig. 3 and 125 this line being where they meet the point 11 of the casing. By this arrangement the entire expansive and impact force of steam, or other fluid is directed against the rear side of vane b^2 to drive the cylinder forward. The chamber into which the steam 130 is received is somewhat diamond shaped in cross section and the vanes being spiral it runs to a point at its front end which is closed by the rear edge of the groove the

rear outer corner of the vane and corner of angle 11 in the casing. As the cylinder turns this chamber continually widens at its rear end while said closed forward pointed 5 end continually moves toward the other end of the section of the cylinder until it suddenly opens into the exhaust ports 8 and the spent steam is discharged through exhaust pipes D². By having a multiplicity of inlet 10 ports, arranged to discharge into the chamber of cylinder B at different points the supply of steam is prevented from being cut off from the chamber behind one vane by the following vane at any point, which is important as, by this means, live steam may be 15 supplied at all points behind each vane. While two ports or only a single port may be found sufficient under some conditions, and the valve D may be adjusted to use only the 20 number of ports the conditions of the work require, when the engine is under a heavy load or great speed is required the three ports arranged substantially equi-distant apart are of great advantage. By reference 25 to Fig. 4, which shows the same position of ports as shown in Fig. 2 except that the valve is turned to open the exhaust ports, as when the engine is reversed, as shown in Fig. 3; it will be seen that the inlet ports 30 also serve as auxiliary exhaust ports and thus prevent any compressing of exhaust fluid between the vanes. When it is desired to reverse the engine the valve is shifted to open the ports 5, 6 and 7 as indicated in 35 Fig. 3 (or any part of them) when the steam is admitted through said ports and exhausted through exhaust port 4, and the then auxiliary exhaust ports 1, 2 and 3, which are thus opened, as shown in Fig. 4.

40 The oil reservoir E is mounted on casing A, and supplied with oil through pipe e, from any source, and said oil is fed through the several branch pipes e', e², e³, e⁴, to the chamber of the cylinder C and is taken into 45 the grooves e² of said cylinder and thus forms an oil packing in the pocket between the bottom of said grooves and the crown of the vanes b². Said oil flows through said grooves from the center toward each 50 end when the engine is operating in one direction and from the ends to the center when operating in the other direction, the rotary action of the cylinder serving to keep the oil in circulation through the pipes, reservoirs and grooves. Oil ports a⁵ lead from 55 within said cylinder each way to the bearings for the journals B and B' in the heads A and A² in the casing. Said journals are thus lubricated and all wearing parts of 60 the surface of the cylinders kept thoroughly oiled to insure against unnecessary wear and friction and the oil, at the same time, serves as a packing to prevent leakage of steam into said grooves and through said grooves 65 into the other parts of the engine.

Having thus fully described my said invention, what I claim as new and desire to secure by Letters Patent, is:—

1. In a rotary engine, the combination of the casing containing communicating cylindrical chambers of different diameters, a pair of cylinders of uniform diameters mounted in said chambers with their surfaces in longitudinal contact, one of said cylinders being formed with spiral vanes 75 and the other with grooves, said grooves and vanes running from a divisional point toward each end of the respective cylinders in opposite directions and formed to fit snugly and co-act with each other and the face of 80 said vanes being on a line coincident with the interior surface of the chamber containing the cylinder bearing them, substantially as set forth.

2. In a rotary engine, the combination of 85 the casing having cylindrical chambers of different diameters, a pair of rotary cylinders of uniform diameters with co-acting grooves and vanes formed thereon mounted in said casing with their peripheries in contact, said vanes being of a form on their edges to fit snugly in said grooves when in mesh and with their faces on the line where their advancing sides separate during rotation from the advance corner of said grooves, 95 substantially as set forth.

3. In a rotary engine, the combination of 100 the casing containing cylindrical chambers, the circles of the interior of two of which cut into each other forming inwardly projecting points 11 between them, a pair of rotary cylinders in said chambers one of which is formed with spiral grooves and the other with spiral vanes which are adapted to mesh and coact therewith, the outer advance corner of each vane and the outer advance corner of each groove being arranged to separate at the angle 11 in the casing between the cylinders, whereby said groove may be closed by said casing before the 110 steam is admitted behind said vane, substantially as set forth.

4. In a rotary engine, the combination of 115 the casing having cylindrical chambers formed therein, and formed with multiple inlet ports on one side and exhaust ports on the other, said inlet ports being arranged to discharge into the cylinder chamber at different circumferential points around one side, a rotary valve for controlling said inlet and exhaust ports mounted in the chamber at the top of said casing, and a pair of cylinders with inter-meshing grooves and vanes mounted in chambers in said casing with their surfaces in contact, substantially 120 as set forth.

5. In a rotary engine, the combination of 125 the casing containing a plurality of cylindrical chambers, two of which cut into each other longitudinally, a rotary cylinder 130

- mounted in each of said chambers with their peripheries in longitudinal contact, one of said cylinders being formed with spiral vanes and the other with spiral grooves, said 5 vanes and grooves being formed to intermesh, the grooves being formed to fit said vanes snugly at their sides but of greater depth than the height of said vanes, where- by a pocket is formed to receive and hold 10 the crown of said vanes, and the valve for controlling the inlet and exhaust ports, substantially as set forth.
6. A rotary engine comprising a casing containing two coaxial cylinders with in- 15 ter-meshing vanes and grooves, the vanes being formed with sides curved to correspond with the curvature of the sides of said grooves and with outer faces curved in cross section to coincide with the inner circum- 20 ference of the chambers in which the cylinder is mounted, substantially as set forth.
7. In a rotary engine, the combination of the casing formed with cylindrical chambers, a pair of coaxial cylinders mounted 25 in said chambers one formed with spiral grooves and the other with spiral vanes meshing therewith, each of said cylinders being formed in two sections abutting at the
- center and the grooves and vanes on one sec- 30 tion running in a right-hand direction and on the other section in a left-hand direction and meeting in the center of said cylinder, substantially as set forth.
8. In a rotary engine, the combination of the casing formed in two sections, secured 35 together at the center, having inlet and ex- haust ports at each end of each section, those in the abutting ends meeting and forming single ports, a pair of cylinders mounted in 40 chambers in said casing, each formed in two sections with spiral grooves on one and spiral vanes on the other, each section of each cylinder having its grooves or vanes running in one direction and in the oppo- 45 site direction on the other section, and the vanes and grooves meeting in the center of the respective cylinders, substantially as set forth.
- In witness whereof, I, have hereunto set my hand and seal at Washington, D. C., this 50 2nd day of March, A. D. nineteen hundred and six.
